FLOTATION APPARATUS

Kenneth L. Tatman, Leadville, Colo., assignor to
 Resurrection Mining Company, Leadville, Colo.,
 a corporation of Delaware

Application April 14, 1949, Serial No. 87,437

4 Claims. (Cl. 261—93)

1

This invention relates to froth flotation and has for its object the provision of an improved flotation cell. More particularly, the invention is concerned with the agitation of the pulp to disperse air bubbles and reagents in the pulp, and provides an improved impeller assembly and air supply means which effect a material saving in power and with equal or superior metallurgical efficiency.

In its preferred embodiment my invention comprises a flotation cell having an impeller rotatable on an upright shaft comprising an upper set of blades which forces the pulp downward and a lower set of blades which forces the pulp upward into impinging contact with the pulp forced downward, a hood or shroud over the upper blades and an air duct connected thereto for supplying air at a pressure preferably above atmospheric pressure under the shroud. The pulp forced downward carries air into contact with the pulp forced upward, resulting in a better and more economical dispersion of air and reagents within the pulp. In an especially advantageous embodiment of the invention, I provide a shroud having an upper covering part and a depending annular skirt concentrically disposed with respect to the upper blades, with the lower edge of the skirt advantageously arranged to overhang at least a part of the peripheral edges of the upper blades whereby the air supplied to the shroud enters the pulp stream of the upper blades and is broken into minute bubbles by the impinging pulp from the lower blades. The skirt of the shroud performs the important function of protecting the upper blades from the wearing action of the pulp, thereby greatly increasing their effective life. I prefer to supply air through the duct to the shroud under a pressure greater than atmospheric, as by means of a low pressure blower, and to provide means to vary the air pressure in accordance with the particular operating conditions.

I attribute the material decrease in horsepower necessary to operate the impeller to the directional location of the impeller blades which force the pulp from below upward and outward and the pulp from above and air from the shroud downward and outward, to two moving bodies of fluid meeting at a common plane resulting in such an action that the air is divided into very minute bubbles. The pulp is not only effectively circulated and aerated but the reagents are thoroughly dispersed within the entire mass of pulp. It is important that the impeller be lo-

2

cated in a favorable part of the liquid pulp and the shroud placed quite close to the upper blades, as will later be explained.

In my presently preferred construction I rotate the impeller on a shaft mounted within a tubular member which supports the shroud in concentric spaced relation to the shaft and connect the tubular member to a source of air under pressure.

These and other novel features of the invention will be better understood after considering the following discussion taken in conjunction with the accompanying drawings, in which:

Fig. 1 is a side elevation, with parts removed, of a flotation cell embodying my invention;

Fig. 2 is an end view of Fig. 1;

Fig. 3 is an enlarged fragmentary view of the shroud and impeller;

Fig. 4 is a side view of the lower end of the impeller shaft;

Figs. 5 and 6 are plan views of the upper and lower impeller blades respectively, and

Figs. 7 and 8 are side views of the upper and lower impeller blades respectively.

The flotation machine illustrated in the drawings comprises a rectangular tank for receiving the pulp which may consist of any number of separate cells. The partition 1 divides the tank into two cells 2 and 3. The tank shown has a feed well 4 from which the feed of ore pulp enters the first well of the tank through the adjustable feed opening 5, the pulp flowing from the feed opening through cell 2, under partition 1, and through cell 3 to the discharge opening 6. On the discharge end of the tank is a rectangular shaped box 7 containing a partition 8 adjustable in height by the adjusting member 9. The tailings from the cell tank flow by gravity through the opening 6 and over the adjustable partition 8 to the bottom 10 of the box from which it may be pumped or carried by gravity to its next destination. Along one side of the cell tank is an adjustable weir 11 over which the froth flows. A similar weir may be mounted on the opposite side.

The improved air disseminating and reagent dispersing mechanism of my invention includes an impeller assembly consisting of an impeller 20 having an upper set of blades 21 and a lower set of blades 22, and a shroud 23 with air supply means 34. The impeller is mounted on an upright shaft 24 and the two sets of blades are in vertical spaced relation with respect to each other. The impeller illustrated has four upper blades and two lower blades, although I may use

various combinations of blades in either position. The upper blades are set to force the pulp downward while the lower blades are set to force pulp upward, both blades being inclined about 30° from the horizontal and sloped oppositely. The impeller is preferably formed in two parts to facilitate casting and both parts are keyed to the shaft and held in a fixed position by the set screw 25 and a standard key. The impeller is preferably formed of cast iron although other materials may be used. To facilitate proper mounting and spacing of the blades on the shaft, the upper part has a depending hub 26 while the lower part has an upwardly extending hub 27. These hubs are proportioned to give proper spacing to the blades which ordinarily should be around 4 inches. The shaft 24 rotates in the anti-friction bearing 28 which is held in the bearing housing 29. The bearing housing is supported by a super structure 30 which rests upon the top of the tank or on any other suitable support. The shaft 24 is rotated by the belt 32 and the connected motor 33.

The air shaft or air duct 34, for example a steel or iron pipe, is attached at its upper end to the bearing housing as by means of the flange 35. Air is supplied to the air duct 34 by the pipe 36 which is connected to the air manifold 37 and which is under an air pressure higher than atmospheric pressure supplied by a low pressure compressor (not shown). The air may be introduced into the duct in any desired volume and pressure, under the control of valve 38. The shroud 23 is detachably connected to the lower end of duct 34 in any suitable manner to facilitate rapid replacement of the shroud during operation of the cells. The shroud comprises a horizontally disposed upper covering part in the form of a disk 41 and a depending annular skirt 42. It will be noted that the disk is only a short distance above the upper blades 21 and that the depending skirt overhangs the upper blades for approximately half their vertical depth, for example, approximately $\frac{1}{2}$ inch below the upper edge. The shroud disk and skirt are spaced from the upper blades sufficiently to provide suitable clearance, for example, $\frac{1}{2}$ inch.

It is advantageous to locate the impeller assembly and shroud in the lower half of the liquid pulp and to maintain the upper level of liquid from 2 to 10 inches below the level of froth discharge. It is understood, of course, that the pulp contains the necessary flotation reagents to result in an appreciable depth of froth above the level of liquid maintained in the cell. With the impeller rotated at a peripheral speed of approximately 2100 feet per minute and with impeller blades inclined from the horizontal around 30°, a very intense agitation of the pulp results.

Any number of similar cells may be used, each provided with the impeller assembly described. As the pulp progresses from the first cell (2) to each succeeding cell (if more than one cell is required), it is successively acted upon by each impeller and circulated and aerated simultaneously. A concentrate is forced over the adjustable weir 11. When the machine is being operated, no pulp is within the air duct 34. The fluid level within the cells must be variable according to operating conditions but is normally some place between the level of the concentrate discharge weir 11 and about 10 inches below.

The invention is also adaptable to flotation cells provided with means for the recirculation of concentrates. The invention contemplates the

use of an impeller, shroud and air duct of the type described to utilize air at atmospheric pressure.

The invention accomplishes an unpredicted very material decrease in the power to effect the desired aeration and dispersion of the reagents. In one operation using a 50 cubic foot machine, the horsepower was reduced about 65% in comparison with modern well-known flotation machines for doing the same work. A decrease in the required power of from 35% to 55% is general.

The invention eliminates the need for stationary baffles for dispersion and the prevention of pulp swirls. The greater proportion of the pulp within each cell is aerated. There are only two parts which are subject to any great amount of wear—the shroud 23 and the impeller 20, both of which are cheap to manufacture and can be replaced in a few minutes without stopping the plant and while the pulp is still flowing through the cell. With the possible exception of the cell or cells in which concentrates are being re-circulated, the impeller can be easily changed without stopping the flow of pulp through the circuit.

I claim:

1. The improvement in flotation cells which comprises an impeller with two sets of blades spaced apart vertically and arranged in the cell to rotate within the liquid pulp, the upper blades being set to force the pulp downward, the lower blades being set to force the pulp upward into impinging contact with the downwardly moving pulp, a shroud over the upper blades having a depending skirt concentrically disposed with respect to the upper blades, and means for supplying air under pressure under the shroud which is drawn downward along with the pulp by the upper blades.

2. A flotation cell according to claim 1 which comprises an air duct connected to the shroud, means for supplying air under a pressure above the atmospheric pressure to the duct, and means to control the volume and pressure of air supplied to the shroud.

3. The improvement in flotation cells which comprises an impeller with upper and lower blades spaced apart vertically and arranged in the cell to rotate within the liquid pulp, the upper blades being set to force the pulp downward, the lower blades being set to force the pulp upward into impinging contact with the downwardly moving pulp, a shroud over the upper blades and laterally disposed therearound, and duct means for supplying air under the shroud at a sufficient pressure to prevent entry of pulp in the duct means during operation of the cell.

4. The improvement in flotation cells which comprises an impeller with upper and lower blades spaced apart vertically and mounted on an upright shaft and arranged to rotate within the liquid pulp, the upper blades being set to force the pulp downward, the lower blades being set to force the pulp upward, an air duct surrounding the shaft, means for supplying air under a pressure above atmospheric pressure to the air duct, a shroud attached to the air duct in open communication therewith having a portion extending laterally from the air duct which is spaced above the upper blades and an annular depending skirt which at least partially surrounds the upper blades, whereby the air entering the shroud is drawn downward along with the pulp by the upper blades and is broken into minute bubbles by contact with the pulp moving

5

upward from the lower blades the pressure of air being sufficient to prevent entry of pulp into the air duct.
